POLISHING MACHINE

Melvin V. Triggs, Alhambra, Calif.

Application January 23, 1948, Serial No. 3,860

3 Claims. (Cl. 51—32)

1

The present invention relates to polishing machines, and has for an object the provision of a machine adapted to polish instrumentalities such as soap dishes which generally have a border flange and a semi-cylindrical shaped soap receiving portion. A semi-cylindrical surface is difficult to polish evenly, and the present invention has its parts so arranged that the entire surface of the soap receiving portion is contacted and polished.

A further object is the provision of a polishing machine which may be manipulated to perform a polishing operation with great rapidity and without fatiguing the operator.

A further object is the provision of a polishing machine so constituted as to handle a large number of devices to be polished.

A further object is the provision of a polishing machine for polishing intricately shaped articles, and which machine is at all times under the direct control of the operator.

A further object is the provision of a polishing machine of simplified design, affords ease of operation, and is generally superior to polishing machines now known to the inventor.

With the above mentioned and other objects in view, the invention consists in the novel and useful provision, formation, construction, association, and relative arrangement of parts, members and features, all as shown in one embodiment in the accompanying drawings, described generally, and more particularly pointed out in the claims.

In the drawings:

Figure 1 is a front elevation of the polishing machine,

Figure 2 is a top plan view of the machine shown in Figure 1,

Figure 3 is a sectional view on the line 3—3 of Figure 1,

Figure 4 is a fragmentary sectional view on the line 4—4 of Figure 3,

Figure 5 is a view similar to Figure 4, certain parts of the machine being in a changed position from that of Figure 4, and,

Figure 6 is a transverse sectional view on an enlarged scale, taken on the line 6—6 of Figure 3.

Referring now with particularity to the drawings, the present polishing machine is adapted to perform a polishing operation upon soap dishes of various sizes as, for instance, illustrated in Figure 2, at 1, and which dishes have an edge or border flange 2 and a concavity 3, the concavity being semi-cylindrical in form, the curve extend-

2

ing between two opposite and parallel flanges 4 and 5, while end walls 6 and 7 close the sides of the concavity, the end walls merging with the parallel flanges 8 and 9.

After a dish of the character shown at 1 has been plated, it must be polished. Generally, this polishing is a hand operation, and polishers of different forms may be used. Unless the polishing is well done, there will be areas in the concavity which are semi-polished or left unpolished. This detracts from the appearance of the dish and may affect its salability. With the polishing machine of the present invention, dishes like that described, having intricate surface configuration, may be readily polished, the polishing being substantially the same throughout the dish.

The machine for accomplishing the polishing includes a turntable 10 which is so formed as to hold a large number of dishes. This turntable 20 in the present instance has a circular outline, and is provided with a base 11, a curved side wall 12, and a top 13. The base and the curved side wall are welded or otherwise secured together in liquid-tight relationship. The top wall 15 may be welded or otherwise secured to the side wall, and said top wall is provided with a plurality of work-receiving openings 14. The work receiving openings will vary in size, in accordance with the work, as illustrated in Figure 2, wherein certain of the openings are larger than others thereof. Furthermore, the outline of the openings will vary, as is self-evident. Secured to the side wall 10 are a plurality of radially extending handles 15 which the operator may grasp when he desires to rotate the turntable. The turntable mounting consists of a central hub 16 having end flanges which engage the top and bottom walls of the turntable. Said turntable is held in adjusted positions upon the sleeve 17, 30 which sleeve extends through the hub, said sleeve carrying an adjustable collar 18 which bears against the lower flange of the hub. The sleeve is mounted upon a standard 19. This standard has a cylindrical side wall 20, a top wall 21, the top wall being secured to one end of the sleeve by welding or otherwise, and the top wall is centrally bored at 22.

Passed through the sleeve is an elongated tube 23, which tube is passed through the bore 22 in 50 the standard and is braced within the standard by means of a bushing 24 held centrally of the standard by an annular plate 25. A fitting 26 is secured to the lower end of the tube 23. A foot operated lever 27 is pivoted at 28 to a support 29 carried on a base 30 for the standard,

and which lever is passed through diametric slots 31 and 32 in the lower portion of the standard, there being a link 33a between the lever and the fitting 26. The lever at one end is adapted to carry an adjustable pile of weights 33 while the opposite end of said lever has a foot portion 34. In the showing of Figure 3, it is evident that when the weights are in the position shown that the foot portion of the lever is elevated, which will elevate the tube 23. To prevent rotation of the tube 23, the said tube is provided with an elongated slot 35, and the sleeve 17 carries a screw 36, one end of which is received in the slot 35.

Secured to the top of the tube 23 is a platform designated generally as 37, the same including a plate 38 transversely secured to the top of the said tube in any appropriate manner, such as by welding. Secured to sides of the said plate are a pair of substantially parallel tracks 39 and 40. While the tracks may take any cross section desired, the present ones are of angle type. Carried on the tracks is a wheeled carriage, designated generally as 41, which carriage includes a flat plate 42 provided with flanged wheels 43. In the present instance there are four flanged wheels, two for each side of the carriage, as shown in Figure 2. The flanged wheels are suitably mounted upon axles, designated generally as 44, the wheels being secured to the axles in any appropriate manner, such as by the cotter pins shown at 45. To assure that the carriage will at all times be maintained on the tracks, side brackets are provided at 46 and 47, said brackets being of angle form, with one leg 48 of each thereof secured to the plate 42, while the opposite leg 49 of each bracket carries a flanged wheel, see Figure 1, at 50, which has engagement with one leg of the track. In this manner, the wheeled carriage is prevented from any displacement from the tracks. Bolted to the top of the platform 41 is an electric motor 51. Pivoted to one of the tracks, at 52, is a lever 53, there being a link 54 between the said lever and the bracket 46. Movement of the lever 53 about its pivot point, will move the wheeled carriage backwardly or forwardly relative to the tracks. The plate 42 carries upright thereon a block 55 provided with bearings 56. A shaft 57 is supported by said bearings. One end of said shaft through the medium of a coupling 58 is secured to the shaft 59 of the motor 51.

An arm 60 is formed in two parts 61 and 62, the parts being relatively adjustable so as to vary the length of the arm by slotting the part 62 in several locations, as illustrated at 63, and passing bolts through member 61 and through the slots of arm 62, as see Figures 1 and 3, the part 61 of said arm at its upper end being provided with a pair of bearings 64 carried on shaft 57. Part 62 carries at its lower end, polishing wheels designated generally as 65. The lower end of part 62 carries a pair of spaced bearings 66 and 67, there being a pulley wheel 68 interposed between said bearings with the said wheel keyed or otherwise secured to a tubular type hub 69, the said hub having internal, oppositely pitched screw-threads 70 and 71, whereby through the medium of screws 72, polishing discs 73 may be secured to the hub. These polishing discs are backed by concave plates 74, whereby the polishing discs, which may be formed of felt or other material, are given a cup-like form as illustrated in Figure 6. Interposed between the pair of bearings 64, and mounted on shaft 57, is a pulley 75

wheel 75. A continuous belt 76 is passed between the upper and lower pulley wheels 68 and 75. To protect the worker against injury resultant upon contact with the continuous belt, I provide a guard designated generally as 77. This guard may take any form desired, although in the present instance, each guard side is of channel cross section as best illustrated in Figure 2. Secured to the arms 60, specifically the part 62 thereof, is an arm or handle 79. The bearing arrangement at the upper end of the arm is such as to allow an oscillating movement of the arm on the shaft 57.

In order to properly secure the work in position on the turntable, and likewise to guard the operator against any injury, I have provided for each work-receiving opening a guard 80, which is fixed to the top of the turntable, and a swing guard 81. These guards are adapted to overlie flanges 4 and 5 of the work to be polished, and in such a manner as to maintain the said work within a work-receiving opening of the turntable. The fixed guards 80 constitute members having base portions 82 which are spacedly secured by means of bolts 83 to the top of the turntable, with an upright plate portion 84, which is to say a portion substantially at right angles to the top of the turntable, and a slightly angled extremity 85. The arrangement is such that the flange 5 of the work may be received between the top of the turntable adjacent the work-receiving opening and the portion 82, as see Figure 1. The swing member is similarly formed in that it has a base flange 86, which is swingingly secured by means of a bolt 87 to the top of the turntable, with an elongated upright plate portion 88 and an inclined upper edge 89, corresponding in form to the portion 85. Thus, the member 81 may be swung on its bolt so as to be free of the flange 4 or swung over the flange, the flange of the work then being interposed between the base flange 86 and the turntable top.

The operation, uses and advantages of the invention just described are as follows:

When work of different sizes is placed within the work receiving openings 14 of the top plate 13 of the turntable, as for instance illustrated in Figures 2 and 3, the work is secured in each instance between one of the fixed flanges and one of the swing flange members so as to hold the work to the turntable. As shown in Figure 3, the concave or curved bowl portion of the work will be confined within the turntable. As the operation of polishing the bowl of the work generates heat, I have provided an arrangement in the turntable whereby the heat is dissipated, and I may, within the purview of the invention, fill the turntable with a liquid, as indicated by the dotted lines at 90. This liquid may be a continuously flowing one, or it may be poured within the turntable and drained therefrom by means of a base plug 91. When it is desired to polish the bowl of the soap dish illustrated, the operator may place his foot upon the foot portion 34 so as to lower the polishing discs 73 within the said bowl and thereafter the turntable may be rotated by grasping one of the handles 15, accompanied by a lowering of the polishing discs for contact with the surface of the bowl. By grasping the handle 53 and moving the same, the carriage which supports the motor and the swing arm, may be moved backwardly or forwardly during rotation of the polishing discs. Upon reference to Figures 4 and 5, it will be observed that first 75 the outer then the inner polishing disc is brought

into contact with the surface of the bowl to be polished. By cupping the felt discs, as illustrated in Figure 6, damage to the bowl is prevented because only the felt disc contacts the bowl. No metal portions which support the felt discs are brought into contact with the bowl. It is evident that after adjusting the two members 61 and 62 of the arm that lowering of the tube 23 will position the polishing discs within the bowl so that the contact may be light or heavy, as desired. The operator may swing the turntable, which is to say, revolve it about the sleeve 17, at the same time swinging the arm 60 to bring the polishing discs into contact within the bowl, in the manner illustrated in Figures 4 and 5. Such movement is chordal to the turntable. As polishing of the bowl generates heat, this heat is dissipated by providing a cooling medium, such as water or other liquid 90 within the turntable. Raising and lowering of the platform with the associated motor, bearings, and the arm, is accomplished by depressing the lever 27 which, it will be noted, is counter-balanced by the weights 33. These weights are sufficient to maintain the tube in its upper position, as illustrated in Figure 3. Slight pressure upon the foot portion of the lever 27 will lower the carriage, with its associated mechanism, so that the polishing discs are brought into contact with the bowl of the work.

Actual practice of the invention has demonstrated that all parts of the bowl in the soap dish illustrated are contacted and that a high polish results. The method of securing the work within the work-receiving openings of the turntable allows for rapid insertion of the bowls within the work-receiving openings and likewise equal rapid removal therefrom. Furthermore, when the polishing discs are rapidly rotated, the operator is protected from bits of polishing material striking the operator by means of the guards 80 and 81, such material striking said plates.

It is, of course, evident that the motor 51 may be energized from a source of electric current, with the usual switches provided in the circuit.

I claim:

1. In a polishing machine, a standard, a sleeve carried by the standard, an elongated tube passed through said sleeve with one end thereof received within the standard, a lever provided with a counter-balance weight secured to the lower end of said elongated tube, a turntable provided with

work-receiving openings rotatably positioned on the sleeve, a platform carried by the upper end of said elongated tube, a dirigible carriage for movement on the platform, an electrical motor and its shaft supported on the dirigible carriage, a polishing wheel, means between said motor shaft and said wheel for rotating the polishing wheel when the motor is energized, and a swing support carried by the motor shaft for the polishing wheel, movement of the counter-balanced lever raising or lowering the platform to control the position of the polishing wheel relative to the work-receiving opening of the turntable.

2. In polishing machine construction, a cylindrical standard, a bearing sleeve axially carried by said standard, an elongated tube passed through the bearing sleeve with one end thereof confined within the standard, means keying the elongated tube against rotation, a turntable rotatably secured on said sleeve, a motor supported on the upper end of said elongated tube, means for shifting the position of the motor in two directions, a polishing wheel, means between the motor and the said wheel for rotating the wheel, and means for mounting the polishing wheel for swinging movement relative to the turntable.

3. A polishing machine, including a turntable formed with openings for receiving work, a polishing wheel positioned above the turntable openings for receiving work, a dirigible carriage, means for mounting the carriage above said turntable and for diametric movement relative to said turntable; an electrical motor and its shaft supported on the dirigible carriage, means between the motor shaft and said polishing wheel for rotating same when the motor is energized, and a freely movable swing support carried by the motor shaft for the polishing wheel.

MELVIN V. TRIGGS.
